UNITED STATES PATENT OFFICE.

MICHAEL FRANK BROGAN, OF LAWRENCE, MASSACHUSETTS, ASSIGNOR TO UNITED SHOE MACHINERY COMPANY, OF PATERSON, NEW JERSEY, A CORPORATION OF NEW JERSEY.

WORK-SUPPORT.

1,182,074.

Specification of Letters Patent. Patented May 9, 1916.

Application filed July 11, 1912. Serial No. 708,908.

To all whom it may concern:

Be it known that I, MICHAEL FRANK BROGAN, a citizen of the United States, residing at Lawrence, in the county of Essex and 5 State of Massachusetts, have invented certain Improvements in Work-Supports, of which the following description, in connection with the accompanying drawings, is a specification, like reference characters on 10 the drawings indicating like parts in the several figures.

This invention relates to work supports for holding boots and shoes in position to be operated by shoe machines and is herein 15 shown and described by way of exemplification as particularly adapted for supporting shoes for the operation of a heel breast- 20 ing machine.

The heel breasting operation consists in 25 removing the surplus material from the front face or breast of the shoe heel and is generally performed by a machine having a knife mounted for vertical reciprocation, the shoe being held with its shank at approximately a right angle to the knife. It is usual to have the breast face cylindrically concave and hence a gouge-shaped knife is used.

In modern lasts the thimble which is provided to receive the last pin is not in the 30 transverse center of the heel portion of the last but is displaced to one side in a right last and to the other side in a left last. It is accordingly necessary to provide lateral 35 movement of the last relatively to the knife so as to bring the center of the knife to the center of the heel. In some styles of heels, moreover, particularly high heels, it is usual to make the angle between the breast and 40 shank somewhat acute and to effect this result the forepart of the shoe is elevated to locate the heel at the proper angle to the knife, the last being so mounted as to permit this movement. It is found, however, 45 when high heels are placed at a great inclination to the knife the line of pressure exerted by the knife is apt to fall to the rear of the transverse axis about which the shoe is tilted, thereby causing the forepart 50 of the shoe to rise with consequent failure of the breasting operation and liability of injury to the heel.

It is the object of this invention to provide a last pin mounting for a work support which, while compact enough to enter

the smallest shoe, will provide the necessary horizontal movements for adjusting the center of the breast to the center of the knife, and also allow movements of the shoe in a vertical plane to enable any desired inclination to be given to the breast face relatively to the trade face of the heel.

An important feature of the invention consists in a last pin which is mounted on a support for movement in a vertical plane 65 about a transverse axis located adjacent to the lower end of the last pin, that is, approximately at the crown of the last. For this purpose the support comprises two parts connected by a segmental guide and 70 guideway for relative movement about an axis located approximately at the base of the last pin and intersecting it. This construction enables the pin to be placed at various angles to the plane of the knife so that the 75 breast face may be given any desired inclination relatively to the tread face of the heel, and obviates any danger of the line of action of the knife falling back of the center of movement of the last pin. Preferably also the segmental guide is provided 80 with means for adjusting and holding it in any desired position of adjustment. This means may consist of a worm which engages teeth formed upon the curved face of the 85 guide. The worm is journaled in the portion having the guideway for the segmental guide and is provided with convenient means for turning the worm to adjust the 90 position of the pin.

Another feature of the invention consists in a last pin mounting having a plurality of rectilinear slides which allow considerable adjusting movement of the last pin laterally to bring the median line of the heel 95 of a shoe, located on the pin, centrally beneath an operating tool, as for example a breasting knife, combined with a segmental slide to allow variation of the position of the last pin in a vertical plane perpendicular to the plane in which the lateral adjusting movement is made.

The construction of the mounting is so compact that the top or leg of a small shoe may be placed over it in putting the last 105 upon the last pin. As shown, the last pin mounting consists of a base adapted to be secured to a jack post or other support, a last pin carrier, and an intermediate section located between the carrier and the base,

and having connection with each for rectilinear sliding movement in the same direction, for example parallel with the edge of the breasting knife. The intermediate section comprises two portions which are connected for movement in a circular arc, the center of which lies approximately at the lower end of the last pin and permits adjustment of the pin lengthwise of the shoe.

These and other features of the invention will appear more fully from the following detailed description when read in connection with the accompanying drawings, and will be pointed out in the appended claims.

In the drawings, Figure 1 is a perspective view of the work support with the breasting knife shown in dotted lines; Fig. 2 is a central section of the device partly in elevation; Fig. 3 is a similar view of a modification.

The herein shown embodiment of the invention comprises a base portion 2 which is adapted to be clamped upon the upper end of a jack post by a set screw 4. In the upper end of the base 2 a T-shaped guideway 6 is formed which is arranged to extend in the direction of the knife edge, indicated at α , Fig. 1. In the T-shaped guideway of the base 2 is fitted a T-shaped guide 8 upon an intermediate section 10. A notch is made in one side of one of the ribs of the T-shaped guide 8 to receive the end of a set screw 12 which limits the movement of the guide 8 in the base 2 and may be removed when the parts are to be detached.

The intermediate section 10 comprises two portions or blocks 14 and 16 which are connected together by a T-shaped segmental guide 22 and corresponding guideway 20, the guide 22 being upon the upper portion 14 of the intermediate section 10. The movement of the guide 22 in the guideway 20 is limited by a set screw 24 in a manner similar to that already described for the straight guide 8. In the upper portion 14 of the intermediate section 10 is a second straight T-shaped guideway 26 which is arranged in the same direction as the guideway 6, and a T-shaped guide 28 formed on a block 25 which constitutes the carrier of a last pin 32 is arranged to slide freely in said guideway. Movement of the carrier guide 28 in its guideway is limited by a set screw 30 which enters a notch in the last pin carrier guide 28. The last pin 32 is secured in the carrier 25 and at its lower end with regard to its exposed portion is a collar 34, upon which the end of the last thimble or the crown of the last rests when the last is placed on the pin.

The last pin 32 is tapered and is somewhat smaller than the hole in the thimble of the ordinary last. This looseness is provided so that the axis of the cylindrical hole in the thimble need not coincide exactly with the axis of the pin, and the convex upper face

of a collar 34 serves to support the end of the thimble with the axis of the thimble at varying inclinations to the axis of the pin.

In use, the base 2 having been secured firmly to the jack post with the straight 70 slides extending transversely of the shoe or in the direction of the plane of the knife, the shoe is placed upon the last pin or spindle and the jack swung under the operating parts of the breasting or other machine. As the thimble of the last is not usually in the center of the heel portion of the last, that is, is not under the center of the heel seat, the shoe may be moved laterally by reason of the straight guides 75 until the center of the heel is opposite the center of the operating instrumentalities of the machine, as for example the presser plate and knife of the heel breasting machine. The shoe may be tilted vertically 80 about the axis y of the segmental guide which axis lies approximately at the crown of the last until the breast is at the proper inclination to the knife or operating means. The center of movement of the segmental guide is also approximately at the base of the last pin, and therefore, it is practically impossible to incline the shoe to such a degree as to throw the line of pressure of the knife back of the axis of the segmental guide. 85 If desired, the segmental guide may be fixed at any inclination by means of a set screw 90 36, Fig. 2.

In order to permit ready adjustment of the angle of the heel pin on the segmental guideway the modification shown in Fig. 3 may be employed in which the lower face of the segmental guide 22 is formed with worm teeth and a worm 38 is journaled in the lower portion 16 of the intermediate section 10 in a position to engage the teeth on the segmental guide. The worm is provided with a thumb head 40 by which it may be readily turned to adjust the inclination of the last pin 32.

Having described my invention, what I claim as new and desire to secure by Letters Patent of the United States is:—

1. In a last pin mounting for shoe supports, the combination with a base of a last pin carrier, a last pin mounted thereon, and an intermediate section comprising portions arranged for relative curvilinear movement about a point adjacent to the lower end of the last pin, said base and carrier being mounted for relative rectilinear movement in a direction perpendicular to the plane of said curvilinear movement.

2. A last pin mounting for shoe supports comprising a base, and a last pin mounted for movement in an arc upon the said base in the plane of the median line of the shoe, the said base having adjacent to said arc a rectilinear slide arranged substantially at right angles to the plane of said arc whereby the 130

last pin may be adjusted transversely of the longitudinal axis of the shoe.

3. A last pin supporting and adjusting device for breasting machines, comprising a base adapted to be secured to the work support of said machine, a plurality of blocks having sliding engagement with each other, the lowermost of said blocks having sliding engagement with said base, both said sliding movements being substantially straight and parallel and extending transversely of the longitudinal median line of the heel, and a last pin mounted for adjustment in a circular arc upon one of said sliding blocks, said arc lying substantially in the plane of said median line.

4. A shoe support comprising a last pin, a base, and connections between the pin and the base whereby the pin may be adjusted in a direction lengthwise of the shoe about an axis located approximately at the crown of the last and intersecting the last pin.

5. A shoe support comprising a last pin, a base relatively to which the pin may be adjusted in a direction lengthwise of the shoe about an axis located approximately at the crown of the last and intersecting the last pin, and means for effecting such adjustment and maintaining the last pin in its adjusted position.

6. A last pin mounting for shoe supports comprising a last pin, a base, and sliding connections between the pin and the base permitting relative movement of the parts in an arc struck from a point located in the last pin and approximately at the crown of the last, and extending in a direction to permit adjustment of the pin lengthwise of the shoe, one portion of said connection having a toothed formation and a coöperating adjusting worm carried by the other portion of the connection and engaging said teeth.

7. A last pin mounting for shoe supports

comprising a last pin, a base, intermediate blocks between the pin and the base, one of which permits limited sliding movement of the last pin thereon transversely of the shoe, and the other of which has a similar movement in the same direction on the base, and a connection between said two blocks which permits adjustment of the last pin about a center near its lower end and a movement of its upper end in the direction of the length of the shoe.

8. A last pin mounting for shoe supports comprising a base having a straight guideway formed therein, a block guided in the guideway and having therein a segmental guideway located in a plane at right angles to the straight guideway, a second block guided in the segmental guideway and having a guideway therein parallel to the straight guideway, a carrier mounted in said last-named guideway, and a last pin on said carrier.

9. A last pin mounting for shoe supports comprising a base having a straight guideway formed therein, a block guided in the guideway and having therein a segmental guideway located in a plane at right angles to the straight guideway, a second block guided in the segmental guideway and having a guideway therein parallel to the straight guideway, a carrier mounted in said last-named guideway, a last pin on said carrier, means for limiting the movement of the blocks in the straight guideways, and means for adjusting and holding the block in the segmental guideway.

In testimony wherof, I have signed my name to this specification in the presence of two subscribing witnesses.

Copies of this patent may be obtained for five cents each, by addressing the "Commissioner of Patents,
Washington, D. C."

It is hereby certified that in Letters Patent No. 1,182,074, granted May 9, 1916, upon the application of Michael Frank Brogan, of Lawrence, Massachusetts, for an improvement in "Work-Supports," errors appear in the printed specification requiring correction as follows: Page 1, line 14, after the word "operated" insert the word *upon*; same page, line 62, for the word "trade" read *tread*; and that the said Letters Patent should be read with these corrections therein that the same may conform to the record of the case in the Patent Office.

Signed and sealed this 20th day of June, A. D., 1916.

[SEAL.]

J. T. NEWTON,

Acting Commissioner of Patents.
